UNITED STATES PATENT OFFICE.

ROMANTA D. WOODFORD, OF CORTLAND, NEW YORK.

DESIGN FOR AN AXLE END.

SPECIFICATION forming part of Design No. 34,380, dated April 16, 1901.

Application filed October 30, 1900, Serial No. 34,956. Term of patent 7 years.

To all whom it may concern:

Be it known that I, ROMANTA D. WOODFORD, a citizen of the United States, residing at Cortland, in the county of Cortland and 5 State of New York, have invented and produced a new and original Design for an Axle End, of which the following is a specification, reference being had to the accompanying drawings, forming part thereof.

10 Figure 1 is a view in side elevation of an axle end embodying my design. Fig. 2 is a top or plan view of the same. Fig. 3 is an end view of the same.

15 My design relates to that part of an axle located at the outer ends and is embodied in the axle end, which forms a distinct article of manufacture.

20 As shown in the drawings, the axle end *a* is curved in one direction toward the center and terminates in a reverse curve near the outer end.

The essential and distinguishing feature of my design resides in the axle-arm *b*, forming the outer end of the structure, in combination with a projection *c*, extending upward 25 from the upper surface of the axle-arm and then forward, terminating in a cylindrical portion *d*, arranged with its axis parallel with the axis of the axle-arm. This cylindrical portion *d* is provided with flanges located at 30 some distance apart, one at or near the end, and giving to the portion a spool-form appearance.

Having described my invention, what I claim as new, and desire to secure by Letters 35 Patent, is—

The design for an axle end as herein shown and described.

ROMANTA D. WOODFORD.
